COMBINATION BRASSIÈRE AND SLIP

Eleanora Garnett, New York, N. Y., assignor to
 "Mme E. Garnett," New York, N. Y., a partnership

Application September 17, 1949, Serial No. 116,292

4 Claims. (Cl. 2-73)

1

This invention relates to women's garments and more particularly to an improved one-piece garment which combines a brassière and a slip, such garments being known as "bra-slips."

A principal object of the invention is to provide a bra-slip adapted to be worn with strapless dresses or with dresses having a plunging neckline.

A bra-slip made according to the invention comprises a brassière portion including a front section of non-elastic material, side sections of elastic material secured to the front section, and rear sections of non-elastic material secured to the side sections. The brassière portion, preferably at the back, has opposed vertical edges forming an opening extending from the top to the bottom of the brassière portion. The several sections of this portion extend vertically and form a waist-line above the lower edges of the sections. A skirt portion is joined along its upper edge to the bottom of the brassière portion below the waist-line and has an opening extending vertically from the top of the skirt and terminating a substantial distance below the juncture of the brassière and skirt portions. The skirt opening has opposed vertical edges forming continuations of the opposed vertical edges of the brassière opening. The skirt and brassière openings are adapted to be closed by a zipper, the elements of which extend along the opposed edges of the openings from the bottom of the skirt opening to the top of the brassière opening. The skirt portion preferably has only one vertical seam, which is aligned with the zipper closure.

The brassière portion is provided with flexible stiffening ribs extending vertically from the top of the brassière portion and terminating at their lower ends in the region of the juncture between the brassière and skirt portions. In the preferred construction, the front section of the brassière portion is made of four vertical pieces joined together at adjacent side edges to form contours conforming to the natural contours of the bosom, and the flexible stiffening ribs are secured to the brassière portion at the junctures of the several pieces and sections, as well as along one edge of the vertical opening.

For a better understanding of the invention, reference may be had to the accompanying drawings, in which:

Fig. 1 is a developed view of the upper part of a preferred form of the new garment;

Figs. 2 and 3 are front and rear views, respectively, of the garment shown in Fig. 1;

Fig. 4 is an enlarged detail view of part of the

2

inside of the garment, showing one of the stiffening ribs secured to the brassière portion, and

Fig. 5 is a sectional view on the line 5-5 in Fig. 4.

5 The garment as illustrated comprises a brassière portion 10 and a lower skirt portion 11. The brassière portion 10 comprises a front section made up of four vertical pieces 12a, 12b, 12c and 12d secured together at adjacent edges, the front 10 section being made of a non-elastic material. The brassière portion also comprises two side sections 13a and 13b made of elastic material and secured to the front section, and rear sections 14a and 14b made of non-elastic material and secured to the side sections. The side sections 13a and 13b, which may be made from sheer nylon elastic material, are adapted to fit under the arms and extend slightly to the back, whereby the brassière is self-adjusting and automatically 15 hugs the figure. The vertical pieces 12a, 12b, 12c and 12d of the front section are cut and sewed together to form contours conforming to the natural contours of the bosom.

The front, side and back sections of the brassière portion 10 extend downward and form a waist-line 15 above the lower edges of these sections. At the back of the brassière, the rear sections 14a-14b are provided with opposed vertical edges 16a and 16b, respectively, which form a 20 rear central opening extending from the top to the bottom of the brassière portion.

The skirt portion 11, which may be made either for a narrow-skirt dress or for a full-skirt dress, is joined along its upper edge to the bottom of the brassière portion 10 about 2" below the waist-line 15, as by means of suitable stitching 18. The skirt portion is provided in back with opposed vertical edges 19a and 19b forming a back opening in the skirt. The edges 19a and 19b also form continuations of the opposed vertical edges 16a and 16b, respectively, of the brassière portion. The vertical opening defined by the edges 19a-19b of the skirt portion extends downward but terminates about 7" below the 25 waist-line 15, as shown at 20. The central back opening in the brassière and skirt portions is adapted to be closed by single zipper 21, the track elements of which extend along the opposed edges 16a-19a and 16b-19b. Thus, with one zipper 20 closing, the rear opening of the garment is closed from the top of the brassière portion to well below the waist-line and the top of the skirt portion. The skirt portion 11 is provided with a single vertical seam 22, which is aligned with the 30 back opening of the garment.

The brassière portion 10 is provided with a number of flexible stiffening ribs 24 which are spaced laterally along the brassière portion and extend vertically from the top of the brassière portion and terminate at their lower ends in the region of the juncture 18 between the brassière and skirt portions. As shown, a rib 24 is located at each juncture between the elastic side sections 13a-13b and the adjacent front or rear sections of the brassière. Another flexible stiffening rib 24a is located along one of the opposed edges 16b forming the rear opening of the brassière. A similar rib 24b is located at the juncture of the two centermost pieces 12b and 12c of the front section, and additional ribs 24c are located at the junctures between the vertical pieces 12a and 12b and between the vertical pieces 12c and 12d. The ribs 24c are curved somewhat at their upper portions to conform to the natural contours. The various ribs may be made of flat coils of wire to give them the desired flexibility, and they preferably extend somewhat below the juncture 18 between the brassière and skirt portions.

Referring to Figs. 4 and 5, I have there illustrated an example of the manner in which the flexible ribs may be secured to the brassière portion. The rib 24b is shown at the seam 25 between the centermost pieces 12b and 12c of the front section. These pieces are provided with flaps 121b and 121c, respectively, extending away from each other and from the seam 25 at the inside of the garment. The flexible rib 24b has an outer fabric covering 26 and an inner fabric covering 27 which are secured along their side edges to the flaps 121b and 121c, as by means of stitching 28.

I claim:

1. A garment comprising a brassière portion including a front section made of four non-elastic vertical pieces secured together at adjacent side edges to form contours conforming to the natural contours of the bosom, side sections of elastic material secured to the outer pieces of said front section, and rear sections of non-elastic material secured to the side sections and having opposed vertical edges forming a rear opening extending from the top to the lower edge of the brassière portion, said sections extending vertically and forming a waist line above the lower edges of the sections, a skirt portion joined along its upper edge to the bottom of the brassière portion below the waist line, a flexible stiffening rib secured to the front section at the juncture of each outer vertical piece and its adjacent vertical piece, the ribs being curved to conform with said contours and extending vertically from the top of the front section to the region of the juncture between the brassière and skirt portions, said skirt having a back opening extending vertically from the top of the skirt portion and terminating a substantial distance below the juncture of said portions, said skirt opening hav-

ing opposed vertical edges forming continuations of the opposed vertical edges of said rear sections of the brassière portion, and a closure having zipper elements extending along said opposed edges from the bottom of the skirt opening to the top of the brassière portion.

2. A garment according to claim 1, comprising also a rib secured to one of said rear sections along an edge of said rear opening, the last rib extending vertically from the top of the brassière portion and terminating at its lower end in the region of the juncture of the skirt and brassière portions.

3. A garment comprising a brassière portion including a front section made of four non-elastic vertical pieces secured together at adjacent side edges to form contours conforming to the natural contours of the bosom, side sections of elastic material secured to the outer pieces of said front section, and rear sections of non-elastic material secured to the side sections, the brassière portion having opposed vertical edges forming an opening extending from the top to the lower edge of the brassière portion, said sections extending vertically and forming a waist-line above the lower edges of the sections, a skirt portion joined along its upper edge to the bottom of the brassière portion below said waist-line, a flexible stiffening rib secured to the front section at the junction of each outer piece and its adjacent piece, the ribs being curved to conform with said contours and extending vertically from the top of the front section to the region of the juncture between the brassière and skirt portions, said skirt having an opening extending vertically from the top of the skirt portion and terminating a substantial distance below the juncture of said portions, the skirt opening having opposed vertical edges forming continuations of the opposed vertical edges of the brassière portion, and a closure having zipper elements extending along said opposed edges from the bottom of the skirt opening to the top of the brassière portion.

4. A garment according to claim 1, comprising also a substantially straight stiffening rib secured to the central part of the front section at the juncture of the two centermost pieces of said last section.
